UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

PICKER-STICK MOTION FOR LOOMS.

Application filed February 9, 1925. Serial No. 7,773.

This invention relates to a familiar type of picker stick motion for looms and the object of the invention is to provide a new, improved and simplified construction by 5 means of which the force or tension of the spring, which serves to restore the picker stick to its normal position, may readily be adjusted as required.

The object of the invention is further 10 to provide a simple and effective means for this purpose which may readily be attached to existing looms without alteration of the rocker stand.

These and other objects of the invention 15 will appear more fully from the accompanying description and drawings and will be particularly pointed out in the claims.

In the drawings:

Fig. 1 is a front elevation of the lower 20 corner of a sufficient portion of a loom to illustrate the present invention.

Fig. 2 is a front elevation of a portion of the rocker stand, together with a preferred form of the present invention.

Fig. 3 is a view in vertical cross section 25 taken on the line 3—3 of Fig. 2.

Fig. 4 is a view in horizontal cross section taken on the line 4—4 of Fig. 2.

Fig. 5 is a view similar to Fig. 2 showing 30 another form of the invention.

Fig. 6 is a view similar to Fig. 2 showing a third form of the invention.

Fig. 7 is a view in side elevation, partially broken away, showing the construction 35 illustrated in Fig. 6.

Fig. 8 is a view in side elevation looking toward the left and partially broken away, showing the construction illustrated in Fig. 5.

Fig. 9 is a detail in rear elevation of the support and engaging and disengaging means shown in Fig. 6.

As the general type of picker stick motion to which this invention relates is well known 45 and familiar to those skilled in the art, it is only necessary to illustrate and describe that portion of the mechanism particularly concerned with the present invention.

A rocker stand 1 presenting a flat upper 50 surface 2 and rigidly secured to the lay rocker shaft 3 is mounted for oscillating movement in the loom, one of the side frames 4 of which is illustrated. The usual picker stick 5 projects down through a slot in the rocker stand and has secured thereto a rocker

shoe 6, the lower surface of which is formed on a convex curve of such a character that as the shoe rocks on the surface 2 of the rocker stand, the effective end of the picker stick will move in substantial parallelism with 60 the lay of the loom. The picker stick is given its picking movement through a connection 7 and is returned to its normal or outermost position through the agency of a spring 8, usually of the helical type. 65 This spring acts to rotate a drum 9 to which is connected one end of a strap 10, the other end of which is secured at 11 to the picker stick.

The tension of this spring not infre- 70 quently becomes relaxed, or lost motion or mal-adjustment occurs in the mechanism which renders it necessary to adjust the tension of the spring. While various provi-

sions have been made for such adjustment, 75 they have been of such a nature as to make it awkward or difficult for the operative readily and quickly to effect an accurate and positive adjustment. The present invention provides a simple and effective 80 means for taking care of this adjustment which may be readily fitted to the rocker stand of existing looms without alteration thereof.

The rocker stand is provided near its center at the front with a depending bracket arm 12, usually cast as a part of the rocker stand. This arm serves to support the spring and the drum. In the preferred form of this construction a spindle 13 projects rearwardly from this bracket arm beneath the rocker stand and is mounted for rotary adjustment in the bracket arm. Upon this spindle is mounted a member in the form of a sleeve 14. This sleeve is keyed 85 to the spindle. For this purpose the spindle is shown at its rear portion at 15 as of polygonal shape, and the sleeve at the rear portion is shown as solid and fitting the spindle. While the spindle and sleeve 90 are thus conveniently formed as separate elements, since they are keyed together it is not necessary, in the broader aspects of the invention, that they should thus be separate elements.

The drum 9, already referred to, is rotatably mounted on the sleeve and thus on the spindle and is shown as having, for that purpose, a hub 16 fitting over the solid portion 100 of the sleeve. The helical spring 8, already 105

referred to, has one end 17 hooked into a slot in the sleeve at the front, and the other end 18 passed up through a slot 19 in the periphery of the drum. The spring thus surrounds the front portion of the sleeve and the hub of the drum, and is connected at the one end to the sleeve and at the other end to the drum, and is arranged to turn the drum counter-clockwise. The strap 10 extends from the picker stick down and up around the periphery of the drum and is conveniently hooked over the end 18 of the spring. Thus the normal action of the spring in its rotation of the drum is to swing the upper end of the picker stick outwardly. The construction is described with respect to the left-hand side of the loom, but will, of course, be similar, but reversed, at the right-hand side of the loom.

A support or supporting member is fitted to and positioned by the bracket arm. In the construction shown in Figs. 1-4, inclusive, this support consists of a metal plate 20 fitting against the front face of the bracket arm 12, held against lateral movement by ears 21 embracing the sides of the bracket arm, and against vertical movement by its being fitted over the front end of the spindle 13. This support, in this form of the invention, is provided with a laterally extending arm 22, having a rearwardly projecting stud 23. On the stud 23 is pivoted a dog 24. This dog is arranged to swing into and out of engagement with the sleeve. The engagement and disengagement of the dog and sleeve is conveniently secured by providing the sleeve at its front end with a circular head 25, the periphery of which is formed with a series of teeth 26 so that the dog can swing in and out from between the teeth. The dog is provided with a weighted arm 27 on the opposite side of its pivot which acts to hold it in its engaging position. The dog also is provided with the upstanding handle 28 and the wing projection 29 overlapping at the rear the head 25. The handle 28 by engaging the adjacent ear 21 prevents the dog 24 from swinging to a position where the weight 27 will not act to return it into engagement with the head 25. The wing 29 prevents the sleeve 14 from moving rearwardly in case the spindle is or becomes loosened but it is so shaped as to allow the sleeve to be removed when the dog is swung to disengaging position.

It will thus be seen that the dog 24 can not move to unlocking or disengaging position of itself. It must be moved by the operative either by pressing upon the handle 28 or weight 27 or by loosening the spindle and winding it up to tighten, or increase the tension of, the spring 8. In either case the dog automatically returns to locking or engaging position.

The dog 24 always locks the sleeve 14 against reverse rotation even if the spindle is accidentally loosened, because such reverse rotation seats the dog in the bottom of the space between the teeth 26 of the head 25 with a toggle-like action.

The spindle 13 is provided at the rear end with a head 30 having a polygonal projection 31, and at the front end is threaded to receive a nut 32. The head 30 abuts against the rear end of the sleeve 14, leaving the drum 9 free to rotate, and when the nut 32 is set up, the spindle, sleeve and bracket arm are all locked rigidly together.

It will thus be seen that no alteration is required in the rocker stand and the depending bracket thereof. A sleeve and spindle is provided of suitable construction and placed in position in the usual manner. The support such as 20 is fitted in place and positioned by the bracket arm and spindle. Thus all the parts are readily positioned on the loom without any alteration of the existing loom structure.

In order to effect an adjustment of the tension of the spring 8, if the tension is to be increased, all that is necessary for the operative to do is to loosen up the nut 32, place a wrench on the head 31 and turn the spindle until the desired rotary adjustment is made. If the tension is to be decreased, the operative, after loosening the nut 32, will swing the dog 24 out of engagement with the head 25 before turning the spindle. Either adjustment is readily made by an operative without assistance and the exact degree of adjustment required is easily secured.

Another form in which the invention may be embodied is illustrated in Figs. 5 and 8. In this case, the support or supporting member 33 is similar to that already described and is fitted to and positioned upon the bracket arm 12 in the same way. The only difference is that the laterally extending arm 34 is simply provided with a threaded aperture in which is threaded a screw pin 35, which when screwed and unscrewed is moved into and out of engagement with the toothed head of the sleeve.

A third form in which the invention may be embodied is shown in Figs. 6, 7 and 9. In this construction the support, or supporting member, comprises the plate 36 fitting against the front face of the bracket arm 12 and having the ears 17 embracing the sides of the bracket arm. But in this case, these ears are connected by the bar 38 at the rear face of the bracket arm 12 and this bar is provided with an integral downwardly projecting lug 39 adapted to fit between the teeth of the toothed head of the sleeve. This supporting member is moved vertically on the bracket arm to bring the lug 39 into and out of engagement with the

toothed head of the sleeve. In order to lock the support in position and maintain the lug 39 in engagement with the toothed head of the sleeve, a latch 40 is pivoted at 41 on the support and hooks over the end of the spindle. The support 36 is slotted at 42 to allow it to slide vertically on the spindle. A nut 43 may be provided at the extreme front end of the spindle to lock the latch 40 in closed position. In this construction, the supporting member 36 and the latch 40 may both be conveniently made of stamped sheet metal.

The constructions illustrated serve to indicate the scope of the invention which in each case is adapted to existing looms without any alteration of the rocker stand or its depending bracket arm and provides a simple and effective means for quickly and easily adjusting the tension of the spring.

Having thus described the invention, what is claimed as new, and desired to be secured by Letters Patent, is:

1. A picker stick motion for looms comprising a rocker stand presenting a depending bracket arm, a spindle rotarily adjustable in the bracket arm, a sleeve mounted upon and keyed to the spindle, a drum rotatably mounted on the sleeve, a spring interposed between the drum and sleeve and connected to both, means for locking the spindle, sleeve and arm together, a support fitted to and positioned by the bracket arm without alteration of the bracket arm, and means carried by the support and movable into engagement with and disengagement from the sleeve thus to hold the spindle and sleeve in any desired rotary position and to permit rotary adjustment thereof.

2. A picker stick motion for looms comprising the construction defined in claim 1, in which the support is held in fixed position on the bracket arm and spindle and the engaging and disengaging means is bodily moved with respect to the support to effect its functions.

3. A picker stick motion for looms comprising the construction defined in claim 1, in which the sleeve is provided with peripheral teeth adjacent the bracket arm, in which the support is held in fixed position on the bracket arm and spindle, and in which the engaging and disengaging means comprises a dog pivoted to the support to swing in and out from between the teeth of the sleeve.

4. A picker stick motion for looms comprising a rocker stand presenting a depending bracket arm, a sleeve carried by and ro-

tarily adjustable with respect to the bracket arm, a drum rotatably mounted on the sleeve, a spring interposed between the drum and sleeve and connected to both, means for locking the sleeve in fixed position with respect to the bracket arm, a support fitted to and positioned by the bracket arm without alteration of the bracket arm, and means carried by this support and movable into engagement with and disengagement from the sleeve thus to hold the sleeve in any desired rotary position and to permit rotary adjustment thereof.

5. A picker stick motion for looms comprising the construction defined in claim 4, in which the sleeve is provided adjacent the bracket arm with a peripherally toothed circular head, in which the support is held in fixed position on the bracket arm, and in which the engaging and disengaging means comprises a dog pivoted to the support to swing in and out from between the teeth of the sleeve head.

6. A picker stick motion for looms comprising a rocker stand presenting a depending bracket arm, a sleeve carried by and rotarily adjustable with respect to the bracket arm, a peripherally toothed circular head adjacent the bracket arm on the sleeve, a spring interposed between the drum and sleeve and connected to both, means for locking the sleeve in fixed position with respect to the bracket arm, a support fitted to and mounted in fixed position on the bracket arm without alteration of the bracket arm, a dog horizontally pivoted on the support and acting normally to swing in between the teeth of the sleeve head and lock the sleeve against rotation induced by the spring.

7. A picker stick motion for looms comprising the construction defined in claim 6, together with a wing connected with the dog and overlapping the rear of the circular head to maintain the dog and circular head in alignment in case of accidental loosening of the sleeve.

8. A picker stick motion for looms comprising the construction defined in claim 6, in which the dog is weighted to cause its normal movement and in which a projection is provided on the dog to contact with the support and prevent the dog from moving to a position out of control of the weight.

In testimony whereof, I have signed my name to this specification.

HARRY A. DAVIS.
